UNITED STATES PATENT OFFICE

VERNON E. CORNELL, OF CLEVELAND, OHIO, ASSIGNOR TO THE STEVENS METAL PRODUCTS COMPANY, OF NILES, OHIO, A CORPORATION OF OHIO

METALLIC RECEPTACLE AND CLOSURE THEREFOR

Application filed January 25, 1930. Serial No. 423,333.

My invention is an improvement in metallic receptacles or containers, and relates more particularly to closures for the same and means for effecting a fluid tight seal between 5 the receptacle and the closure.

One of the objects of my invention is to enable metallic receptacles such as drums or barrels to be fitted with a full removable cover providing a tight fluid proof seal between 10 the cover and the receptacle, without aid of tools.

Another object of my invention is to removably secure a cover upon a metallic receptacle and to exert a pressure in a line substantially parallel with the axis of the receptacle to seat the cover on the receptacle to effect a fluid tight seal.

Another object of my invention is to insure a fluid tight seal between the cover and the receptacle by uniformly distributing the sealing pressure about the periphery of the cover.

A further object of the invention is to seal the cover against unauthorized removal.

Other objects and advantages of my invention will become more apparent from the following description of two embodiments thereof, reference being made to the accompanying drawing in which like reference 25 characters are employed to designate like parts throughout the same.

In the drawing—

Fig. 1 is a top plan view of one form of my invention, showing the cover on the receptacle in fluid tight sealed relation.

Fig. 2 is a similar view of a modification of my invention in which the clamping or locking ring is split in a plurality of places.

Fig. 3 is an enlarged fragmentary section 40 taken on line 3—3 of either Figs. 1 or 2.

Fig. 4 is a fragmentary plan view of the locking or clamping ring contracted to seal the cover on the receptacle.

Fig. 5 is a similar view to Fig. 4 except 45 that the ring is shown partly expanded as in removing the ring and cover from the receptacle.

Fig. 6 is an elevation of the locking or clamping ring looking in the direction of 50 the arrows in Fig. 4.

My invention is particularly applicable to metallic containers or receptacles such as barrels or drums and the like, which are provided with a circumferential bead at their open ends for supporting a cover and for 55 reinforcement purposes.

Referring first to Figs. 1 and 3 to 6 inclusively, in which I have illustrated the preferred embodiment of the present invention, the barrel or drum is indicated at 1. 60 The upper edge of the container is rolled to form a peripheral bead 2 at the open end thereof. A cover 3 comprising a cupped member having a peripheral upwardly and outwardly extending flange 4, is supported 65 by the bead 2 in such a manner that the cupped portion of the cover may be telescoped for a short distance within the container, as illustrated in Fig. 3. It will be noted that a portion of the flange 4 is slightly arcuate in cross section, to conform with the approximate curvature of the upper surface of the bead, and that the outer edge of the flange terminates at a point near that defined by the greatest outer diameter of the 70 bead. Although I have shown the flange extending to a point equal to the greatest outer diameter of the bead, I find that the flange may extend to a point just short thereof, it being sufficient that the flange extend completely over the packing member 5 between 75 the flange and the bead. This packing member may consist of an annulus of any suitable packing material, and I have found that an annulus of flexible rubber tubing is very 80 satisfactory for this purpose.

I have provided a simple means for removably securing the cover on the receptacle to effect a fluid tight seal between the same by exerting a substantially uniform pressure on 85 the cover and bead in a direction substantially parallel to the axis of the container.

In the present embodiment this means includes a split contractible channeled clamping ring 6 substantially U-shaped in cross 90 section and provided near its ends with inwardly extending lugs 7. The upper and lower flange and bead engaging walls respectively of the ring extend in substantially parallel planes only near their inner edges as 100

shown more clearly in Fig. 3. Thus it will be seen that upon contraction of the ring the flange will be pressed tightly against the packing 5 and the supporting bead 2 under a substantially vertical pressure. The lugs 7 may be formed integrally with the ring or formed separately of the ring and welded thereto in a plane defining the upper inwardly extending side wall of the ring. The lugs 10 are apertured to receive the pins 8 near the inner extremities of the lugs. A lever 9 is pivotally secured by one of the pins to one of the lugs 7, while a link 10 is pivotally secured at one end to the other lugs, the ends of the link being slightly offset longitudinally. 15 The opposite end of the link is pivotally connected by a pin 11 to the lever 9, the pin 11 being located at a point on the lever which normally lies between an imaginary straight line drawn through the pins 8, and the adjacent ring body when the parts are in the position shown in Fig. 4. In this manner, when the lever is moved to the ring contracted position as shown in Fig. 4, the pivot point 20 defined by the pin 11 will have moved slightly past the dead center line of the pins 8, thereby preventing accidental release of the lever under the stresses set up by the contracted ring.

30 When it is desired to seal the container against unauthorized opening, a tab 12 may be welded to the ring at a point where its opening 13 will register with an opening near the outer end of the lever when the lever is 35 swung toward the ring. The customary wire seal may be then inserted in the openings and sealed in the usual manner.

Referring more particularly to Figs. 4, 5 and 6, I have illustrated a means contemplated by this invention, for exerting a lateral pressure against the cover flange, which results in the ring being drawn inwardly and more easily contracted about the bead and cover flange. This means includes an arm 14 formed on the lever 9 extending preferably at an obtuse angle therefrom. The outer end of this arm is formed with a shoe 15, the outer or flange engaging wall of which is tapered slightly inwardly and forwardly as shown 45 more clearly in Fig. 5. By inclining this wall, relative movement between the shoe and the flange, upon swinging the lever 9, will be more easily accomplished. The arm 14 is of sufficient length to engage the flange under 50 considerable lateral pressure and to cause the ring 6 to be tightly contracted about the bead and flange to press the same tightly together when the lever 9 is moved to the position in Fig. 4, thereby exerting and uniformly distributing a sealing pressure between the flange and the bead.

In Fig. 5 I have shown the lever 9 and ring 6 in partly opened position to allow the ring to assume its normal open position and to release the lateral pressure on the cover and

ring. By further moving the lever 9 to the right in Fig. 5, the ring may be expanded to a point where its circumference is greater than the circumference of the flange or bead, to permit its removal from the receptacle. In 70 this manner the cover and packing ring may be lifted from the receptacle, to permit cleaning the same or for emptying or filling the same.

In Fig. 2 I have illustrated a modification 75 of the present invention. In this embodiment the contracting ring is split at points substantially diametrically opposite, although I do not limit the invention in this respect, since the ring may be split at any other 80 points along its circumference. In the figure the ring comprises complementary sections 6 and 6', two of its adjacent ends being hingedly connected together by means of a link 20 pivotally connected at its end to the lugs 21.

The lugs 21 are similar to the lugs 7 and may be formed integrally with or welded to the upper lateral wall of the ring sections. In this embodiment, of course, the inherent 90 resiliency of the ring as a unit is greatly diminished, and the ring possesses a degree of flexibility as a unit, which aids to a high degree in uniformly distributing the pressure on the flange and bead when the lever 9 is closed, and which therefore enables a 95 tight fluid proof seal between the cover and the receptacle to be made.

In other respects this modification is similar in structure to the form shown in Figs. 100 1 and 3 to 6 inclusive.

It is to be understood that while I have shown my invention applied to receptacles having openings of the same diameter as the inner diameter of the receptacle, the invention is equally applicable to receptacles having 105 restricted openings.

It will also be observed that by my invention the full removable cover may be clamped easily on the receptacle in fluid sealing contact and may be removed easily without the aid of tools.

In my copending applications Serial Numbers 423,334, 423,335 and 423,336 all filed January 25, 1930, I have disclosed several other types of closures for metallic receptacles.

Various changes may be made in the details of construction and arrangement of parts without departing from the spirit of 115 the invention or the scope of the subjoined claims.

I claim:

1. The combination with a metallic receptacle having a bead rolled about its open end, and a removable cover for said receptacle having a marginal flange fitting over the bead, of a segmental contractible channeled clamping ring having walls engageable with and pressing the flange and bead together when 120

the ring is contracted, and means for contracting the ring and simultaneously exerting a lateral pressure on the cover flange.

2. The combination with a metallic receptacle having a bead rolled about its open end, and a removable cover for said receptacle having a marginal flange fitting over the bead, of a segmental contractible channeled clamping ring having walls engageable with and pressing the flange and bead together when the ring is contracted, and means for contracting the ring and simultaneously exerting a lateral pressure on the cover flange, and a link hingedly connecting adjacent ends of the sections together.

3. In a clamping device for a receptacle having a bead rolled about its opened end and a cover having a flange fitting over the bead, a segmental contractible channeled clamping ring having walls engageable with and pressing the flange and bead together when the ring is contracted, and means for contracting the ring including a lever pivotally connected to one segment of the ring and a link pivotally connecting said lever with another segment of the ring.

4. In a clamping device for a receptacle having a bead rolled about its open end and a cover having a flange fitting over the bead, a segmental contractible channeled clamping ring having walls engageable with and pressing the flange and bead together when the ring is contracted, and means for contracting the ring including a lever pivotally connected to one segment of the ring and a link pivotally connecting said lever with another segment of the ring, and a link hingedly connecting the ring segment carrying the lever with said other segment.

40 In testimony whereof, I hereunto affix my signature.

VERNON E. CORNELL.
